ABSTRACT

A compact combination lever ship's steering system is disclosed having unitary control features permitting ready selection of either of two preferred modes of operation. The ship's pilot may select lever operated proportional control of the ship's rudder steering engine with a direct display of rudder position for reference. The same combination lever control may be used for direct control of the ship's steering engine, rudder position again being displayed.

COMBINATION LEVER SHIP'S STEERING SYSTEM

BACKGROUND OF THE INVENTION

FIELD OF THE INVENTION

Prior art ship's steering systems have generally been of the type in which a wheel or a lever controller has been used without follow up for control of the ship's steering engine. Turning the controller to the right or to the left actuates the steering engine which moves the rudder in a corresponding direction until a limit stop is reached or until the controller is centered. The pilot may make judgments about the ship's response after its response is well established, but generally has no direct or convenient means for determining with significant accuracy at the time a turn is commanded what that response will ultimately be.

Other types of prior art steering systems provide proportional control of the ship's rudder with full follow up so that rudder response is more directly related to the magnitude of commanded turn. However, such systems are generally complex and, being complex, may suffer disabling failures. Such systems generally do not lend themselves to ready location of the point of failure. When failed, they may not provide a sufficiently reliable degree of standby operation.

SUMMARY OF THE INVENTION

A compact combination lever steering system for ships is provided with a unitary lever controller permitting the ship's pilot to select either of two modes of control of the ship's rudder steering engine. In a first control mode, the pilot may select lever operated control of the ship's steering engine and its rudder and may observe the turning performance of the ship in part by viewing a direct display of rudder angle as a reference. The display and the lever controller are in close proximity so that lever command and rudder response are readily correlated. The combination lever controller may be used in a second mode, if desired, for direct control of the ship's steering engine without follow up. Rudder position is again displayed, the apparatus for proportional control being always on standby duty for instant selection by the pilot.

BRIEF DESCRIPTION OF THE DRAWINGS

FIG. 1 is a perspective view of the combination lever controller.

FIG. 2 is a top view of a portion of the controller of FIG. 1.

FIG. 3 is a cross section view of a portion of the apparatus of FIGS. 1 and 2

FIG. 4 is a cross section view of the apparatus of FIGS. 1 and 2 taken along the line 4-4 of FIG. 2.

FIG. 5 is a partial interior elevation view taken along the line 5-5 of FIG. 4.

FIG. 6 is a diagram of the electrical circuits used in the invention.

DESCRIPTION OF THE PREFERRED EMBODIMENT

FIG. 1 presents a view of the lever steering actuator of the novel ship's steering system as normally seen by the pilot. A waterproof casing 1 is provided in which the steering lever 2 is pivoted for angular motion, as

will be explained, and in which is also conveniently located a zero-center electrical meter or indicator means 3 on which the pilot may continuously view a representation of rudder actual position relative to its null position whenever the steering system is operating. A cap 4 on the half-circular housing 7 above the pivot shaft for lever 2 bears an index marker 5 corresponding to the proper null position for lever 2. A raised marker 6 on top of the lever 2 adjacent the frontal portion of cap 4 cooperates with index 5 to enable accurate nulling of lever 2. As will be seen, the position of lever 2 is proportional to rudder order when operating in the full follow up mode.

The upper face 8 of the portion of casing 1 in front of meter 3 supports metal blocks 9 and 9a symmetrically on either side of housing 7. As will be seen, blocks 9 and 9a are provided with longitudinal bores for accommodating respective spring-positioned pins 10 and 10a.

Pin 10, when impacted by the vertical face 11 (not directly seen) of lever 2 acts as a first resilient mechanical stop. Likewise, pin 10a, when impacted by the vertical face 11a of lever 2, acts as a second resilient mechanical stop.

The structure of the apparatus of FIG. 1 may be more fully appreciated by examination of FIGS. 2, 3, 4, and 5, wherein parts similar to those in FIG. 1 are given the same reference numerals. In FIG. 2, it is seen that cap 4 is fastened to the half-circular shell housing 7 by

screws 12, 12a, and 12b and that lever 2 extends under the cap 4 where it is fastened at its inner end to vertical shaft 13. FIGS. 2 and 3 show more clearly the nature of the resilient mechanical stops comprising blocks 9 and 9a. For instance, FIG. 3 shows block 9 and pin 10,

block 9 being provided with a cylindrical cavity 14 for accommodating a stiff helical wire spring 15. Pin 10 is provided with a head 16 slideable within bore 14 and provides a first seat for spring 15. At its other end, spring 15 abuts the inner face of a screw or other plug 17 fitted in a mating threaded enlargement 18 of cavity 14. When the face 11 of lever 2 is forced against the rounded end 19 of pin 10, the latter is moved inward along its axis, carrying head 16 inward and compressing spring 15.

FIGS. 4 and 5 illustrate elements of the lever steering actuator internal of casing 1. Shaft 13 and its lower extension 13a are mounted for angular movement in a bearing (not shown) within the central inward projection 20 of casing 1. A gear 21 meshes with a second gear 22 on potentiometer shaft 23, potentiometer 24 having three electrical leads 25 for purposes which will be explained. The potentiometer 24 is mounted within casing 1, being fixed to an inner wall of casing 1 by bolts 26, 26a, and mount 28.

The lever shaft extension 13a drives a switch cam 27, seen more clearly in FIG. 5, for operating switch 30 or switch 30a when lever 2 is moved to an extreme right or left position that depresses one of the pins 10, 10a.

Switches 30 and 30a are symmetrically mounted with respect to the null position of lever 2 and therefore of switch cam 27 on base 280 by screws 31, 31a, 32, 32a. Base 280 is, in turn, fixed to an inner wall of casing 1 by screws 29, 29a.

Switch 30 is provided with an actuator button 35 moved by arm 33 when arm 33 is urged toward actuator button 35 by the rotation of arm 33 about pivot 34.

Such rotation of arm 33 occurs when the face 37 of switch cam 27 impacts a roller 39 located at the button (35) end of arm 33. Impact of face 37 on roller 39 and the consequent closing of switch 30 occur when the face 11 of steering lever 2 pushes stop pin 10 into block 9 against spring 14.

In a similar manner, switch 30a, which is not seen in FIG. 4 for purposes of convenience, is provided with an actuator button 35a moved by arm 33a when arm 33a is urged toward actuator button 35a by the rotation of arm 33a about pivot 34a. Motion of arm 33a occurs when the face 37a of switch cam 27 impacts roller 39a found on the button (32a) end of arm 33a. Impact of face 37a and roller 39a and the consequent closing of electrical switching contacts within switch 30a occur when the face 11a of lever 2 pushes stop pin 10a into a block 9a against its associated spring. When lever 2 is released, spring 15 or spring 15a will push its associated stop pin 10 or 10a outward, moving lever 2 and cam 27 back so that both switches 30 and 30a are open. It is to be noted that the angularly separated switches 30 and 30a are respectively equipped with electrical leads 36 and 36a, whose purposes will become apparent. It is also seen that casing 1 supports a dual position switch 40 whose control handle 41 is accessible outside of casing 1. Manual selector switch 40 is provided with electrical leads 42 whose purpose will become apparent.

The apparatus shown in FIGS. 1 to 5 is employed by the ship's pilot to control the electrical servo and control system of FIG. 6 for operation of the ship's rudder 50 in one of two selectable modes. A first mode may be termed a proportional control mode with full follow up, rudder position being fed back as a term used in the amplifier elements of the system along with commands inserted by moving the steering lever 2. Rudder position is shown on meter 3. In a second selectable mode of operation, which may be referred to as the emergency mode, the amplifier elements of the system are not used, but meter 3 is still caused faithfully to show rudder position. The relative positions of lever 2 and meter 3 permit the pilot at all times to judge the response of the ship's rudder in relation to the position of the steering lever.

In FIG. 6, a conventional source 51 of alternating current power may be used to excite rectifier 52 and also to supply electrical energy to the system output power amplifier 53. The unidirectional voltage output from rectifier 52 is supplied via electrical leads 54, 55 to potentiometer leads 25a, 25b, across the resistor 56 of potentiometric device 24. The tap 57 of potentiometer 24 is driven by shaft 13a, as seen in FIG. 4, in common with switch cam 27, and has its output lead 25c coupled as one input to power amplifier 53. The output of rectifier 52 is also supplied through leads 54 and 55 and the respective leads 59 and 60 across a series impedance circuit comprising substantially equal fixed resistors 63 and 64.

In addition, the unidirectional voltage output of rectifier 52 is supplied through leads 54 and 55 and the respective leads 61 and 62 across the resistor 66 of potentiometer 65. Potentiometric device 65 has an angularly movable tap 67 driven by the shaft 68b in synchronism with the instantaneous position of rudder 50. Tap 67 is coupled by lead 69 as a second input to power amplifier 53.

Power amplifier 53 may take any of several forms, including known semiconductor or vacuum tube power amplifiers or magnetic amplifiers of the general type disclosed in the DeWestfelt U.S. Pat. No. 2,813,236, 5 entitled "Control System for Electrical Servomotors", issued Nov. 12, 1957, and assigned to the Sperry Rand Corporation. The application of such amplifiers in ship's steering controls is further discussed in various sources such as the Braddon et al. U.S. Pat. No. 2,796,576 entitled "Maneuverable Automatic Pilot for Ships", issued June 18, 1957, and also assigned to the Sperry Rand Corporation.

The output of a device suitable for use as power amplifier 53 will conventionally appear on a set of four electrical leads 70a, 70b, 70c, and 70d. Leads 70a and 70b are connected across coil 80 of differential or power relay 82, while leads 70c and 70d are coupled across coil 81 thereof. Relay 82 includes an armature 83 movable about pivot 84 according to the respective excitation of coils 80, 81 for connecting leads 42a and 42b through contact 85 or for connecting leads 42b, and 42c through contact 86. Relay 82 is a power switching device often employed for the control of ship's steering engines, such as engine 95. It will be apparent that contact 85 is made when one sense of turn is desired, while contact 86 is made if an opposite sense of turn is commanded, as is further explained in the aforementioned Braddon et al. U.S. Pat. No. 2,796,576.

In the above desired arrangement for the first mode of operation of the steering system, the manual selector switch 40, first introduced in FIG. 4, will not be in the position shown in FIG. 6, but manual linkage 93 operated by handle 41 will cause blades 90, 91, and 92 respectively to contact the terminals 87, 88, and 89 of the respective leads 42a, 42b, 42c, electrical leads also seen in FIG. 4. Switch blades 90 and 92 are respectively connected by leads 42d, 42f across the activating coils 96, 97 of rudder steering engine or motor 95. Coils 96, 97 may represent coils of an electrical motor, or may be the control solenoids which, for instance, move the four-way sensitive control valve of a hydraulic servo motor of conventional nature. Switch blade 91 is connected by lead 42e through power source 51a and lead 94 to the center tap 98 between steering engine coils 96 and 97. Power source 51a may by any convenient source of alternating power; sources 51 and 51a may in practice be identical. Depending upon the contacted status of terminals 85 and 86, the ship's rudder steering engine or motor 95 causes rudder 50 to be driven through shaft 68a in one rotational sense or the other.

It is thus seen that the dual bridge circuit comprising potentiometric devices 24 and 65 and their associated circuits provides control signals to power amplifier 53 for operation of relay 82 and consequently for the control of steering engine 95 and rudder 50. The second bridge circuit involving rudder potentiometer 65 and the fixed resistors 63 and 64 also has a role to play during operation of the system in the first mode. It is seen, for example, that meter 3 is connected between lead 69, and therefore the movable tap 67 of potentiometer 65, and the mid-point terminal 99 between resistors 63 and 64. Since resistors 63 and 64 have fixed values, unbalance of the associated bridge by motion of potentiometer (65) tap 66 causes the pointer of meter 3 to

move in synchronism with the movement of rudder 50. Meter 3 will preferably be a taut band suspension zero-center microammeter whose calibration may be effected by positioning tap 100 of a shunting potentiometer 101 placed across meter 3. The deflection of meter 3 is observed in terms of the position of steering lever 2, affording a ready understanding of the behavior of the system at all times.

In the second mode of operation, the handle 41 of switch 40 of FIG. 4 is moved to position the switch blades 90, 91, and 92 as actually illustrated in FIG. 6. In this instance, switch cam 27 and switches 30 and 30a of FIGS. 4 and 5 come into play, along with leads 42g, 42h, and 42i since switch blades 90, 91, and 92 now contact the respective terminals of leads 42g, 42h, and 42i. With lever 2 and therefore switch cam 27 approximately centered, the angularly separated on-off switches 30 and 30a are normally open, being held open, for example, by springs 71 and 72. When lever 2 is moved to its extreme position to engage and move one resilient mechanical stop pin, switch 30 contacts the terminal of lead 36. In this instance, a circuit path is completed along lead 42g, through blade 90 of switch 40, through lead 42d, coil 96 of steering engine 95, lead 94, power source 51a, lead 42e, blade 91 of switch 40, and the common lead 42h back to switch 30.

Should the opposite turn command be desired, lever 2 is moved to depress the opposite resilient mechanical pin and on-off switch 30a contacts the terminal of lead 36a. As a consequence, a circuit path is completed along lead 42i, through blade 92 of switch 40, through lead 42f, coil 97 of steering engine 95, lead 94, power source 51a, lead 42e, blade 91 of switch 40, and the common lead 42h back to switch 30a.

While the bridge circuit associated with potentiometers 24 and 65 is active in the second mode of operation and continues to supply signals to power amplifier 53, such is done on a standby basis. Thus, the output of amplifier 53 is instantaneously available to the pilot by operation of selector switch 40. It will be understood that other choices for the location of manual selector switch 40 may be made, such as a location on lever 2 where it may be used to control a remote relay to move selector switch 40. In any event, the bridge circuit associated with fixed resistors 63 and 64 and rudder potentiometer 65 is enabled to continue to supply rudder position indications on zero-center display 3.

In operation of the system, it is seen that the ship's pilot is given freedom of choice to operate the steering system in the mode he deems most suited to use in the particular circumstances in which he finds his ship. When operating in the first mode, full follow up electrical control is exercised over rudder 50. Since there is no mechanical connection between the lever 2 and the steering engine 95, lever 2 may be positioned with no substantial effort and the rudder 50 will respond to any such movement of lever 2 and may be positioned accurately and quickly at any angle between its two hard-over extremes. When operating in the first mode, hard-over motion of lever 2, even when sufficient to actuate one or the other of the angularly separated resilient stop pins 10 or 10a, does not cause the cam switch 27 to produce any disturbing action even if switch 36 or switch 36a is closed. In addition to using the benefits inherent in proportional control in the first mode, the

ship's pilot has access by virtue of meter 3 to information on the momentary behavior of the rudder 50 and is thus able readily to determine the performance of the control and to detect failure of follow up.

5 Operation in the second mode is available not only for emergency use, but may be preferred by some pilots for use under special circumstances. It will be appreciated that there is less equipment involved in operation in the second mode and that reliability may therefore be inherently greater. Being highly reliable, the second mode apparatus is an effective standby for the majority of pilots which prefer to use proportional control. Operation in the non-follow up mode permits the ship's rudder to move only when lever 2 is held against a stop pin 10 or 10a and rudder movement immediately stops when lever 2 is released.

The versatility of the novel ship's steering system is further seen by consideration of its self-testing qualities. If a failure occurs when operating in the first mode, the pilot can to a substantial degree determine the locus of the failure by moving manual selector switch 40 to its second mode position. If meter 3 remains operative in the mode two condition, there is power present within the bridge circuits and therefore probably no failure of those circuits or of the power supply 51 or rectifier 52. The indication is failure of power supply 51a or of relay 82. However, if meter 3 does not produce a following indication with the system in the second mode of operation, the problem is probably seated in power supply 51, in rectifier 52, in the bridge circuits, or in the power amplifier 53. The steering engine 50 may itself have failed, indicating the need to shift to use of a standby steering engine.

20 30 35 40 45 50 55 60 65 For the ship's pilot preferring to use the direct control featured in the second mode of operation when in close or dangerous situations in which the thought of a possible failure in an electrical control circuit is abhorrent to him, mode two operation may be selected. The pilot is still benefitted, as he was in mode one operation, by the presence of rudder position information on meter 3. Lengthy navigation in the second mode is entirely feasible; in fact, the ship may readily be sailed to home port using the direct control of mode two operation after a failure of a mode one component, where the latter may be more readily repaired or replaced than at a foreign port.

In addition to the simplicity, versatility, and low cost features of the novel control system, it is seen that it readily accommodates addition of other features which are at times found desirable in ship's steering systems. For example, addition of a gyrocompass navigation system is feasible, as well as of means permitting control of the gain of the system according to different loading and speed conditions, or of a weather adjustment circuit, or of other adjustments of the type referred to in the aforementioned Braddon et al. U.S. Pat. No. 2,796,576, in the West U.S. Pat. No. 2,719,502, entitled: "Automatic Pilot for Ships", filed Oct. 4, 1955, and assigned to the Sperry Rand Corporation, and elsewhere.

65 While the invention has been described in its preferred embodiments, it is to be understood that the words which have been used are words of description rather than of limitation, and that changes within the purview of the appended claims may be made without

departing from the true scope and spirit of the invention in its broader aspects.

I claim:

1. Apparatus for operation of a rudder steering motor comprising:

steering lever means movable to the right or left about an axis and between fixed angularly separated extreme positions,

first and second electrical circuit means controllable by said lever means, and

manual selector means for applying electrical power to said rudder steering motor selectively through at least a portion of said first or second electrical circuit means,

said first electrical circuit means comprising bridge means unbalanced by motion of said lever means or said rudder steering motor and supplying an electrical output for determining operation of said rudder steering motor,

said second electrical circuit means comprising switch means closable at said extreme positions of said lever means for supplying an electrical output for determining operation of said rudder steering motor.

2. Apparatus as described in claim 1 comprising: fixed impedance means connected across said bridge means, and

indicator means connected to said bridge means and to said fixed impedance means for displaying the instantaneous position of said rudder independent of the selected state of said manual selector means.

3. Apparatus as described in claim 1 wherein said bridge means comprises:

first and second potentiometric means having 35 respective first and second movable pick off means,

said first pick off means being movable by said steering lever means,

said second pick off means being movable by said 40 rudder steering motor,

said first and second pick off means being adapted for the supply of an electrical output for determining operation of said rudder steering motor, and

power supply means connected across said potentiometric means.

4. Apparatus as described in claim 3 wherein said first and second pick off means supply an electrical output for the differential control of differential relay 50 means for determining operation of said rudder steering motor.

5. Apparatus as described in claim 1 wherein said second electrical circuit means comprises:

first and second switch means symmetrically located 55

respectively at said first and second angularly separated extreme positions, and

cam means positioned by said lever means for actuating said first switch means only at said first extreme position or said second switch means only at said second extreme position.

6. Apparatus for operation of a ship's rudder steering motor comprising:

a casing,

lever means movable to the right or left about an axis between angularly separated extreme positions, shaft means for rotatably supporting said lever means relative to said casing on said axis and extending into the interior of said casing.

potentiometric means within said casing driven synchronously with said shaft means adapted for generating proportional electrical signals representing lever position for selectively controlling said steering motor,

on-off switch means located at said angularly separated extreme positions of said lever means adapted for generating on-off control signals in response to the location of said lever means with respect to said extreme positions for selectively controlling said steering motor, and

means for selecting said proportional or said on-off signals for control of said steering motor.

7. Apparatus for operation of a rudder steering motor comprising:

a casing,

lever means movable to the right or left about an axis between fixed angularly separated extreme positions,

shaft means for rotatably supporting said lever means relative to said casing on said axis and extending into the interior of said casing,

potentiometric means within said casing driven synchronously with said shaft means adapted for generating proportional electrical signals representing lever position for selectively controlling said steering motor,

on-off switch means located at said angularly separated extreme positions of said lever means adapted for generating on-off control signals in response to the location of said lever means with respect to said extreme positions for selectively controlling said steering motor,

resilient mechanical stop means activated by motion of said lever means in a range of positions of said lever means including the angular positions at which said on-off switch means is operated, and

separate switch means for selecting said proportional or said on-off signals for control of said steering motor.
